[57] CLAIM

The ornamental design for an aircraft engine starter, as shown and described.

DESCRIPTION

FIG. 1 is a top, side and end perspective view of an aircraft engine starter showing my new design;

FIG. 2 is a side view thereof;

FIG. 3 is a side view of the opposite side thereof;

FIG. 4 is an end view thereof;

FIG. 5 is an end view of the opposite end thereof;

FIG. 6 is a top plan view thereof;

FIG. 7 is a bottom plan view thereof;

FIG. 8 is a bottom, side and end perspective view;

FIG. 9 is a bottom, side and end perspective of a second embodiment showing my new design; and,

FIG. 10 is a bottom, side and end perspective view of a third embodiment showing my new design.

It being understood that the views not shown to FIGS. 9 and 10 are like those of FIGS. 1 through 8, except for the location of the smaller cylindrical housing.

FIG. 1

FIG. 2

FIG. 3

FIG. 4

FIG. 5

FIG. 6

FIG. 7

FIG. 9

FIG. 10
